UNITED STATES PATENT OFFICE.

LINA PRAGER WEBER, OF NEW YORK, N. Y.

DESIGN FOR AN ARTIFICIAL FLOWER.

SPECIFICATION forming part of Design No. 32,352, dated March 13, 1900.

Application filed February 7, 1900. Serial No. 4,406. Term of patent 31 years.

To all whom it may concern.

Be it known that I, LINA PRAGER WEBER, a citizen of the United States, residing at the city of New York, borough of Manhattan, 5 county and State of New York, (whose post-office address is 96 Bleeker street in said city,) have invented and produced a new and original Design for an Artificial Flower, of which the following is a specification.

10 My invention resides in the artificial flower having as its essential features the particular shape and configuration and its surface ornamentation as hereinafter shown and described.

15 In the drawings forming part of this specification, Figure 1 is a top view; Fig. 2, a side view; Fig. 3, a rear view, and Fig. 4 a front view.

20 In plan the flower partakes of the general appearance of a horseshoe curve. In side elevation the appearance is of a fan with the

handle (or stem) 1 adjacent the rear line, and in rear and front elevation its shape is approximately of an inverted cone. This configuration is given to the flower as a whole by 25 the particular disposition of the petals 2 and corolla 3. The petals are surface ornamented by the radiant stripes 4 and curled-over edges 5, the edges of the petals being serrated.

The effect of this flower is very pleasing, 30 and it has not been known to approximate any known flower in nature.

Having described my invention, I claim—

35 The design for an artificial flower, substantially as herein shown and described.

Signed at the city, county, and State of New York this 5th day of February, 1900.

LINA PRAGER WEBER.
